FREQUENCY STABILIZATION SYSTEM

Hallan E. Goldstine, Port Jefferson, N. Y., assignor to Radio Corporation of America, a corporation of Delaware

Application March 20, 1944, Serial No. 527,189

2 Claims. (Cl. 315—5)

1

This invention comprises a frequency stabilized inductive output electron discharge device circuit.

Inductive output electron discharge device circuits are known in the art. One such circuit, given by way of example only, is described in an article entitled "A wide band inductive output amplifier," published in the Proceedings of the I. R. E., March, 1940, by A. V. Haeff and L. S. Nergaard. Such a circuit includes a cavity resonator having a gap and an electron discharge device for propagating a modulated or interrupted stream of electrons across the gap of the cavity resonator. The passage of the electrons across the gap induces energy in the cavity resonator.

One difficulty heretofore experienced in these inductive output systems has been the reduction in the Q of the system due to the loading on the cavity resonator caused by losses in the electron tube, losses in the glass envelope of the tube, and the loading caused by the power taken from the cavity resonator for utilization purposes. The inductive output system is also somewhat affected by heat from the electron tube, which may also cause the electron stream to depart somewhat from the desired normal path. The heating of the electron tube due to its operation over a period of time often causes the dimensions of the tube elements, including the glass envelope, to change. These changes are reflected in the resonant frequency of the cavity resonator.

The present invention has for its primary object to overcome the foregoing difficulties by stabilizing the frequency of the inductive output system to a high degree, and this is accomplished by the use of a frequency stabilizing element so coupled between the input and output of the system that the frequency of operation is dependent substantially solely upon the characteristics of the frequency controlling element. In the preferred embodiment of the invention, this frequency controlling element is a highly stable, temperature-controlled concentric line resonator of high Q which is coupled between the output of the cavity resonator and the input of the electron discharge device through short coupling lines of relatively low Q. By suitable adjustments, the circulating energy in the concentric line resonator employed as the frequency determining element is made to be large compared to the energy supplied to the input circuit of the electron tube. The phase and magnitude of the feed back energy between the output and input circuits of the inductive output tube is adjusted to give stable oscillating conditions. Because of

the fact that the coupling lines between the inductive output system and the frequency controlling resonator have reasonably broad frequency characteristics, it will be evident that the high Q concentric line resonator is the predominant frequency controlling element.

A more detailed description of the invention follows in conjunction with a drawing, whose single figure illustrates the preferred embodiment 10 of the present invention.

Referring to the drawing in more detail, there is shown an electron discharge device 1, comprising a vacuum tube structure consisting of an evacuated glass envelope 2 containing therein a cathode 3, heater 4, a modulating grid 5, ring-like accelerator electrodes 6, and a collector electrode 7, the latter containing therein a suitable suppressor electrode 8. This type of electron discharge device is now well known in the art and 20 is not being claimed per se, the showing being given merely to illustrate how it fits into the cavity resonator 12 and associated apparatus. By way of example only, this vacuum tube may be an RCA 825 type inductive output tube.

Surrounding the exterior of the electron discharge device 1 in symmetrical fashion, and located intermediate the tube accelerator electrodes 6, there is provided the high Q low loss tank circuit 12 in the form of a cavity resonator 30 constituted by a copper cylinder 13 whose ends are closed by truncated cones made of sheet copper 14 and 15. The dimension of the cavity resonator 12 as measured from the center of the glass envelope 2 toward the arc of a sector shown in dotted lines at 17 is approximately one-quarter 35 of the length of the communication wave corresponding to the resonant frequency. It should be noted that the shape of the resonator 12 departs somewhat from that shown in such copending applications as Serial Nos. 296,045 and 346,106, 40 respectively filed September 22, 1939, by Fred H. Kroger, and July 18, 1940, and now U. S. Patents 2,350,907 and 2,373,233 granted June 6, 1944 and April 10, 1945 respectively, by Orville E. Dow, 45 mainly in the lengthening of the cavity resonator at the extreme edges and in the shortening of the cavity resonator at the center, due to the provision of the cylindrical element 13. In effect, this type of cavity resonator can be referred to as an hour-glass or re-entrant cone type of resonator. The cavity resonator is provided with a gap at 9 across which the electron stream in the device 1 passes. In order to vary the resonant frequency of the cavity resonator 12 to a limited 50 degree, the gap at 9 is made adjustable, one side

of which is formed by a copper plated iron sleeve 10, the other side of which is formed by an iron sleeve piece 11, as a consequence of which there is obtained a variation of the capacity between the sides of the gap. Sleeve 10 is made to move in an axial direction and makes sliding contact with copper springs 50 which are soldered to the side 14 of the resonator. Sleeve 10 is preferably copper plated, in order to provide low loss and a good electrical connection between the elements 14 and 10.

For focussing the electron beam, there is provided a pair of magnetic lenses in series relation, constituted by gaps 9 and 16 formed by spaced iron sleeves 18, 10 and 11 which surround the glass envelope 2 and are serially arranged with respect to an iron magnetic path. This magnetic path includes a strip of iron 19 which is placed adjacent to the sides of the upper sector of the tank 12 and which is completed through an iron core 20, in turn surrounded by an electromagnetic field coil or solenoid 21 excited by a direct current source of supply 22. If desired, the magnetic path may be supplied by a permanent magnet which would then replace the field coil 21 and the yoke 20.

The cavity resonator 12 is maintained at ground potential, while the cathode is maintained at a potential of about 3400 volts negative with respect to ground, thus maintaining the cavity resonator at a potential which is relatively positive with respect to the cathode. The accelerator electrodes 6 are also connected to ground through suitable resistors, as shown, and hence are also at a relatively high positive potential relative to the cathode. The collector electrode 7 is maintained at -2000 volts relative to ground and thus held at a high but lower positive potential than the accelerator electrodes relative to the cathode. The suppressor electrode 8 is connected to a point on a potentiometer connected between -2000 volts and -3400 volts and is thus at a somewhat higher positive potential than the collector electrode relative to the cathode. The potentiometer is adjusted to supply the suppressor with the proper voltage to reduce current to a minimum in the adjacent accelerator electrode, such as might be due to secondary emission from the collector.

In order to stabilize the frequency of the system, there is provided a high Q concentric line resonator 25 having an inner conductor 26 provided at one end with a Sylphon bellows 27. The overall length of the inner conductor 26 is maintained constant despite fluctuations in temperature, by virtue of the Sylphon bellows 27 which is connected to one end of the concentric line resonator by means of the Invar rod 28 of low temperature coefficient characteristic material. By means of suitable elements (not shown), this concentric line resonator is of the type described in Kroger United States Patent 2,108,895, granted Feb. 22, 1938. In practice, the Invar rod 28 passes through one end of the cavity resonator and is fastened to a suitable platform 29 of selected materials for enabling either positive or negative temperature correction, as desired.

The concentric line resonator 25 is coupled to the output of the inductive output system by means of a short length of transmission line 30. Line 30 is coupled at one end to the interior of the concentric line resonator 25 by means of an adjustable loop 31, and is coupled to the interior of the cavity resonator 12 at its other end by means of the adjustable loop 32. Loops 31 and

32 are rotatable in position in order to vary the degree of coupling. At the end of line 30 adjacent the cavity resonator 12 there is provided a circuit comprising a coaxial line stub 33 whose effective length is adjustable by means of a slider 34 which short-circuits and is movable over the lengths of inner and outer conductors of stub 33. A variable condenser 35 is provided between the cylinder 13 of the cavity resonator 12 and that end of the loop 32 which is directly connected to the line 30. Stub 33 is in effect a tuning inductance and this element, in combination with the condenser 35, provides a means for tuning loop 32. The impedance of the line 30 may also be matched to that of the loop 32 by means of suitable adjustments of the line stub 33 and the condenser 35. For a more detailed description of a coupling system for use between a cavity resonator and a utilization circuit, employing a coaxial line stub and a tuning condenser across the coupling line, reference is made to copending application Serial No. 346,106, filed by me and Orville E. Dow on July 18, 1940, now United States Patent 2,373,233, granted April 10, 1945.

The concentric line resonator 25 is also coupled to the input or grid circuit of the electron discharge device 1 by means of a coaxial transmission line 36. One end of line 36 is coupled to the interior of the concentric line resonator 25 by means of an adjustable loop 37 which is rotatable in the interior of the concentric line resonator in order to vary the degree of coupling thereto. The coaxial line 36 is inductively coupled at its other end to the input or grid circuit consisting of loop 38 and variable condenser 39. The grid is connected to the loop 38 by means of an adjustable tap. Condenser 39 at one end of loop 38 serves to tune the grid circuit. Condenser 40 at the other end of loop 38 serves as a by-pass condenser.

Coaxial lines 30 and 36 are made as short as is feasible and are arranged and operated so as to have reasonably broad frequency characteristics; hence, these coaxial lines have much lower Qs than either the cavity resonator 12 or the concentric line resonator 25. The concentric line resonator 25, on the other hand, is a very high Q circuit which has a sharp frequency characteristic, and for this reason this concentric line resonator is of primary importance in controlling the frequency of the system. The feed back path including coaxial line 30, concentric line resonator 25, coaxial line 36 and the associated loops and adjusting elements are so adjusted that the phase of the feed back is suitable for producing stable oscillating conditions. In practice, the cavity resonator 12 may develop as much as twenty watts in its interior, of which only a relatively small amount (such as, let us say, of the order of one watt) is necessary to drive the grid circuit. Another relatively small amount of power of the order of one watt may be used to drive a suitable utilization circuit, such as a power amplifier input circuit which is shown coupled to the interior of cavity resonator 12 by means of adjustable loop 41. The remainder of the power developed in the cavity resonator 12 may circulate in the concentric line resonator 25. Thus, by way of example, there may be about 18 watts lost circulating in the concentric line resonator 25, whereas only one watt of this is used to drive the grid through the coaxial line 36. It will thus be seen that the ratio of the power in the concentric line resonator to the power used to drive the grid circuit is relatively high. These factors all enter into pro-

ducing a highly stable frequency of operation. It is preferred, though not essential, that the impedance of the transmission lines 30 and 36 be approximately matched to the impedances of the circuits at their output terminals so as to minimize standing waves in the lines.

In one embodiment of the type illustrated in the drawing and successfully tried out in practice, there was obtained a high order of frequency stability of the order of two parts per million per degree centigrade, with the transmitter operating on 474 megacycles.

What is claimed is:

1. A frequency stabilized inductive output system comprising a temperature controlled concentric line resonator of high Q having distributed constants, and individual coupling circuits between the output and the input of the inductive output system and said high Q concentric line resonator, said coupling circuits having relatively broad frequency characteristics and having an appreciably lower Q than the Q of said resonator, whereby said concentric line resonator is the predominant frequency controlling element for said system, said coupling circuits comprising short sections of coaxial transmission lines, the coaxial line coupling the output of the inductive system to said high Q concentric line resonator having adjustable loops at both ends for varying the degree of coupling and also having a tuning stub connected thereto, the coaxial line coupling the input circuit of the inductive output system to the high Q concentric line resonator having an adjustable loop at its input terminal located in the interior of said high Q resonator, the output end of said last line being inductively coupled to said input circuit.

2. An inductive output system having a cavity resonator in the form of a surface of revolution and having a gap across which a stream of electrons may pass, a grid electrode on one side of said gap for modulating the intensity of said stream, and a collector electrode on the other side of said gap, a frequency stabilizing circuit comprising a temperature-controlled concentric line resonator of high Q, and individual coupling circuits connected between the output of said cavity resonator and said grid and said concentric line resonator, said coupling circuits comprising short sections of coaxial lines having appreciably lower Qs than the Q of said concentric line resonator, said coaxial lines having relatively broad frequency characteristics, the coaxial line coupling the output of the cavity resonator to said concentric line resonator having adjustable loops at both ends for varying the degree of coupling and also having a tuning stub connected therewith, the coaxial line coupling said grid to said concentric line resonator having an adjustable loop in circuit with one end and which loop is located in the interior of said concentric line resonator.
